CLAIM

The ornamental design for a combination portable and detachable bag, as shown and described.

DESCRIPTION

FIG. 1 is a perspective view of a combination portable and detachable bag showing my new design, the shoulder straps being removed;

FIG. 2 is an enlarged front elevational view thereof, the shoulder straps shown attached;

FIG. 3 is a rear elevational view of FIG. 2;

FIG. 4 is a right side elevational view of FIG. 2;

FIG. 5 is a left side elevational view of FIG. 2;

FIG. 6 is a top plan view of FIG. 2;

FIG. 7 is a bottom plan view of FIG. 2; and

FIG. 8 is an exploded view of FIG. 1.

FIG. 1

FIG. 2
